[57] CLAIM

The ornamental design for the shoe upper, as shown and described.

DESCRIPTION

FIG. 1 is an elevational view of one side of a shoe upper showing my new design;

FIG. 2 is an elevational view of the other side of the shoe upper shown in FIG. 1;

FIG. 3 is a front elevational view of the shoe upper shown in FIG. 1;

FIG. 4 is a rear elevational view of the shoe upper shown in FIG. 1;

FIG. 5 is a top plan view of the shoe upper shown in FIG. 1;

FIG. 6 is an elevational view of a side of a shoe upper showing a second embodiment of my new design;

FIG. 7 is an elevational view of the other side of the shoe upper shown in FIG. 6;

FIG. 8 is a front elevational view of the shoe upper shown in FIG. 6;

FIG. 9 is a rear elevational view of the shoe upper shown in FIG. 6; and,

FIG. 10 is a top plan view of the shoe upper as shown in FIG. 6.

The broken line showing the shoe sole in FIGS. 1-4 and 6-9 is for illustrative purposes and forms no part of the claimed design.

FIG. 1

FIG. 2

FIG. 4

FIG. 3

FIG. 5

FIG. 6

FIG. 9

FIG. 8

FIG. 10
